US00D807923S

(12) **United States Design Patent** (10) **Patent No.:** **US D807,923 S**
(45) **Date of Patent:** **** Jan. 16, 2018**

(54) **INTERFACE PORTION OF A PUMP**

(71) Applicant: **ABBVIE INC.**, North Chicago, IL (US)

(72) Inventors: **Phil D. Anderson**, Libertyville, IL (US); **Kevin Novak**, Park Ridge, IL (US); **Gurjinder Dhami**, Neenah, WI (US); **Scott Smieja**, Oshkosh, WI (US); **Matthew Svacina**, Brillion, WI (US); **Gary Friederichs**, Chilton, WI (US)

(73) Assignee: **ABBVIE INC.**, North Chicago, IL (US)

(**) Term: **15 Years**

(21) Appl. No.: **29/550,455**

(22) Filed: **Jan. 4, 2016**

Related U.S. Application Data

(63) Continuation of application No. 29/513,436, filed on Dec. 30, 2014, now Pat. No. Des. 746,871.

(57) **CLAIM**

The ornamental design for an interface portion of a pump, as shown and described.

DESCRIPTION

FIG. 1 is a perspective view of an embodiment of our design for an interface portion of a pump, with a lock member in an open position.

FIG. 2 is a front view of the interface portion of the pump of FIG. 1.

FIG. 3 is a rear view of the interface portion of the pump of FIG. 1.

FIG. 4 is a left side view of the interface portion of the pump of FIG. 1.

FIG. 5 is a right side view of the interface portion of the pump of FIG. 1.

FIG. 6 is a top view of the interface portion of the pump of FIG. 1; and,

FIG. 7 is a bottom view of the interface portion of the pump of FIG. 1.

The broken lines shown throughout these figures depict environmental subject matter only and form no part of the claimed design.

1 Claim, 6 Drawing Sheets
